UNITED STATES PATENT OFFICE.

JOHN D. CUTTER, OF NEW YORK, N. Y.

DENTAL FLOSS.

No. 872,908.

Specification of Letters Patent.

Patented Dec. 3, 1907.

Application filed April 9, 1907. Serial No. 367,242.

To all whom it may concern:

Be it known that I, JOHN D. CUTTER, a citizen of the United States, and a resident of the city of New York, borough of Brooklyn, in the county of Kings and State of New

5 York, have invented a new and useful Improvement in Dental Floss, of which the following is a full, clear, and exact description.

The invention relates to the construction 10 of dental floss, or a floss adapted to be passed between the teeth for the purpose of cleaning them, and removing foreign substances.

The object of the invention is to construct 15 the floss in the form of a ribbon instead of giving it the accustomed twisted shape, thus enabling the improved floss to be more conveniently entered between the teeth, and to enter narrower crevices than twisted floss; 20 and also in operation the improved floss covers a greater amount of surface.

The invention consists in the novel construction and combination of the several parts as will be hereinafter fully set forth and 25 pointed out in the claims.

Reference is to be had to the accompanying drawings forming a part of this specification, in which similar characters of reference indicate corresponding parts in all the figures.

Figure 1 is a perspective view of the improved floss wound upon a core, and Fig. 2 is an enlarged plan view of a piece of the said floss illustrating the manner in which it is constructed.

The improved floss A may be of any desired length, and is in the form of a ribbon or tape, having opposing flat sides.

The floss is usually cross-wound, as is shown at 11 in Fig. 1, on a core 12, and in the 40 construction of the floss as shown in Fig. 2, any desired number of threads, fibers or filaments 13 are laid in parallelism and in close proximity to each other and are bonded with molten wax 14.

Having thus described my invention, I claim as new and desire to secure by Letters Patent,—

A dental floss consisting of a series of threads laid parallel and in proximity to 50 each other, and a covering of wax for the said threads.

In testimony whereof I have signed my name to this specification in the presence of two subscribing witnesses.

JOHN D. CUTTER.
